PUMPING UNIT

Louis Fincher, Lufkin, Tex., assignor to Lufkin Foundry & Machine Company, Lufkin, Tex., a corporation of Texas

Application December 3, 1949, Serial No. 130,981

7 Claims. (Cl. 103—6)

1

This invention relates to a counterbalancing pumping unit which is adapted to counterbalance the variation of work load between the up-stroke and the down-stroke of a vertically operable pump, as, for example, the pump employed for removing fluid from a well.

It is an object of this invention to provide a pumping unit of this class which counterbalances a variation in work load between the up-stroke and the down-stroke of a vertically operable pump, as for an oil well, by maintaining a constant balance between the fluid pressure in a closed system, including a power cylinder at the top of the well, and the compressed air pressure which operates against the fluid pressure.

It is another object of this invention to provide a pumping unit of this class which is adapted to control the vertical elevation to which the piston within the power cylinder ascends so as to control the level at which the bottom hole pump plunger operates at the bottom of the well.

It is also an object of this invention to provide a pump which when driven in one direction by a prime mover, has means therein for self-reversing its direction of discharge so as to alternately discharge fluid into a power cylinder and into a surge tank.

It is another object of this invention to provide a pumping unit of this class in which a self-reversing pump is adapted to deliver more fluid in one direction of discharge than is delivered in the other direction of discharge.

It is still another object of this invention to provide a pumping unit of this class which has control means therein for maintaining a predetermined balance between the compressed air pressure in an air tank and the fluid pressure in the surge tank of a closed fluid system to which the air tank is connected.

Other and further objects will be apparent when the specification is considered in connection with the drawing, in which:

Fig. 1 is a plan view of the pumping unit;

Fig. 2 is an elevation of the pumping unit taken along line 2—2 of Fig. 1;

Fig. 3 is a sectional elevation of the self-reversing pump as taken along line 3—3 of Fig. 1;

Fig. 4 is a fragmentary sectional elevation of the self-reversing pump taken along line 4—4 of Fig. 1; and

Fig. 5 is a diagrammatical view of the operation of the pressure control device of the pumping unit.

The pumping unit 1 comprises a base 2 having mounted thereon a vertically extending hydraulic cylinder 3 which has a piston 4 therein, the rod 5 of the piston being adapted for connection to the top sucker rod 6 of a sucker rod line which leads down into a well and is connected to a pump plunger, not shown, which picks up fluid at the bottom of the well and transfers it to the top thereof.

2

The cylinder 3, near the top thereof, has a series of vertically aligned valves 8 connected thereto and a line 9 leads from these valves into a reservoir 10. A scavenger pump 11 is mounted above the reservoir and picks up fluid from the line 12 and discharges it through a line 13 into a surge tank 14. The surge tank has a line 15 connected into the top thereof which leads to air cylinders 16 which have air under pressure supplied thereto by the compressor 17 mounted on the base 2 of the unit 1.

The self-reversing pump 18 is mounted for convenience on top of the reservoir 10 and is connected to the surge tank 14 by means of the line 19, and into the power cylinder 3 by means of the line 20 which connects thereto near the cylinder bottom slightly above its base 21. A prime mover 22, as a gasoline engine, drives, by means of the chain or V-belt 23, the sheave 24 which drives the self-reversing pump 18. The scavenger pump 11 may, for purposes of convenience, be mounted on the end of the self-reversing pump 18 as shown in Figs. 1 and 2, and means may be provided for also driving this pump by the prime mover 22. Optionally it may be driven by a separate drive means as a small motor, not shown. The sheave 24 also has the chain or belt 26 connected thereto to drive the compressor, as shown in Figs. 1 and 2.

30 As shown in Fig. 1, the compressed air tanks 16 are supplied by the same compressor 17. These tanks, by means of cross-bars 28, may be connected to the power cylinder 3 so that the air tanks 16 and the power cylinder 3 are cross-braced for structural purposes near the top of the air cylinders and substantially centrally of the power cylinder. To complete the structurally braced triangle of members, the compressed air tanks have outlets 29 which connect into a T 30, 40 into which is connected the line 15 to the surge tank 14. A suitable valve 31 is provided between the self-reversing pump 18 and the line 20, and a valve 32 is also provided in the air line 15 between air tanks and the surge tank 14.

The self-reversing pump 18 as shown in Figs. 3 and 4 may be of substantially the construction disclosed in my co-pending application for a Self-Reversing Rotary Pump, Serial No. 98,287, filed June 10, 1949, now Patent No. 2,625,105. Either of the modifications disclosed in this co-pending application may be employed but preference is given to the modification of Figs. 8—11 thereof since this model of the self-reversing pump is adapted to deliver more fluid in one direction of discharge than it delivers in the other direction.

55 This preferred pump, as disclosed in my Figs. 3 and 4, comprises an outer housing 40 which has a closure plug 41 therefor having threaded holes 42 therein. A boss 43 is provided which has bored and counterbored holes 44 therein so that the boss may be adjustably positioned at any of several points on the closure plug by means of the screws 45. An inner housing 46 is mounted

on the backing plate 47 which is connected to be driven by a transmission, not shown, which is mounted on the shaft 48. This transmission may be of any conventional type. The inner housing has opposed ports 49 and 50 therein which are of greater peripheral width than the adjustable boss 43 or the boss 51 which is integrally cast with the outer housing 40.

An impeller means 52 for transferring fluid is mounted on the shaft 48 and in the form of the invention disclosed, this fluid transfer means is of the vane type although any other conventional type of impeller may be used as well. This impeller rotates with the shaft 48 and at a greater speed than does the inner housing 46 which is driven by the transmission, not shown.

The outer housing 40 has opposed connections 53 and 54 therein with connection axis extending substantially perpendicular to the axis through the bosses 43 and 51. The outer housing also has compartments 55 and 56 therein which are in communication with the slots 57 and 58 respectively. A wall 59 separates the compartments and has the valve seat 60 therein which is controlled by the valve 61. Another valve, not shown, is mounted to control the valve seat 62 in the wall 59, this valve extending oppositely from the valve 61 and opening in the opposite direction in the compartment 55.

The outer housing also has slots 63 and 64 similar to the slots 57 and 58, and all of these slots are tapered in decreasing size toward the bosses 43 and 51.

Let us assume as a starting point that the port 49 of the inner housing is adjacent the connection 53, and the port 50 is adjacent the connection 54. Then with the impeller 52 and the inner housing 46 rotating in a clockwise direction as shown by the arrow in Fig. 3, fluid first enters through the connection 53 and is discharged out through the connection 54. When the inner housing has rotated to the position shown in Fig. 3, fluid circulates as shown by the arrows, part of the fluid taking a path through the outer housing, through the port 49 of the inner housing, through the impeller, and out through the port 50 of the inner housing into the outer housing. The other portion of the fluid takes a similar path through the outer housing on the right side of the pump, through the port 49, through the impeller, and out through the port 50 into the outer housing. It should be noticed that in this type of pump the ports 49 and 50 have greater peripheral width than the bosses 51 and 43 and consequently are never closed. With this construction the deceleration as the inner housing approaches the position shown in Fig. 3, and the acceleration as it moves away from this position, is very gradual. Then, as the inner housing 46 and the impeller 52 continue clockwise rotation past the position of Fig. 3, the direction of fluid flow is reversed, port communication with the outer housing space increases, and fluid flow accelerates.

Should it be desired to discharge more fluid through one connection than is discharged through the other connection, it is only necessary to adjust the position of the boss 43. Should the boss be moved to the left hand side of the housing 40 more fluid will be discharged out of the right hand side of the outer housing through the connection 54 than is discharged through the connection 53 on the opposite stroke.

This is obvious since positioning of the boss 43 to the left shortens the opening between the

boss and the inner housing through which the fluid passes on the left hand side of the pump and increases the width of the opening between the boss 43 and the inner housing 46 through which the fluid may circulate on the right hand side of the pump.

Should the pump tend to deliver an excess of fluid through the compartment 54 over the amount which may be discharged out therethrough, the excess fluid will circulate into the compartment 55, lift the valve 61 from the seat 60, and recirculate into the left hand side of the compartment. Should the pump tend to discharge more fluid out of the connection 53 than can be received out therethrough, the excess fluid will circulate into the compartment 56, lift a valve, not shown, from the seat 62 and discharge through the compartment 55 and into the right hand side of the pump. This over-load feature is not limited to the form of over-load valve disclosed, but any conventional over-load means may be employed for this purpose.

This invention includes a control system which is adapted to compensate for the differences in loads placed upon the pumping unit on the down-stroke and on the up-stroke. The load on the up-stroke is greater than on the down-stroke, as on the up-stroke the unit must lift a weight of fluid plus the weight of the plunger 30 at the bottom of the well and the weight of the sucker rods extending therefrom to the top of the well, and must also overcome friction, whereas on the down-stroke the weight of the sucker rods and plunger are lowered abetted by the force of gravity.

To counterbalance this variation in load occurring in the operation of the pumping unit as a result of the transfer of a volume of fluid from the surge tank into the power cylinder on the up-stroke, and the return of this fluid to the surge tank on the down-stroke, compressed air is maintained in air tanks which communicate with the top of the surge tank, and balance is obtained thereby.

As the fluid is transferred from the comparatively small volume surge tank into the power cylinder on the upstroke, there is no appreciable pressure drop in the surge tank as a result thereof, since the comparatively extra large volume of air in the air tanks permits the air to occupy the space evacuated by the fluid with no noticeable reduction of the pressure in the air tank-surge tank system. This is true even though the pressure developed in the power unit on the up-stroke is about two hundred pounds per square inch and on the down-stroke, about one hundred pounds per square inch. On each up-stroke of the power cylinder, work is being done accelerating the sucker rod string and the oil fluid column thereabove in order to transfer the oil from the well to storage tanks. Consequently, the difference in fluid pressure in the power cylinder, as developed on the up-stroke, and that occurring on the down-stroke, is translated into actual work done on the up-stroke.

Should there be an increase of the load which the pumping unit has to lift, or should there be leakage from the compressed air tank, an overbalance in favor of the fluid pressure occurs so that the plane of equalization between fluid pressure and air pressure occurs higher in the surge tank than the level of a desired plane of equalization. On the other hand, should an excess of air pressure develop, as by the lowering of the well load, or by an increase in the temperature of the

air, then there will be an over-balance in favor of air pressure, and the plane of equalization will occur at a lower point in the surge tank, and below the predetermined plane at which equalization is sought. To compensate for such occurrences, and to strive at maintaining the plane of equalization at a predetermined desired level, the automatic regulating device of this invention is provided.

The device by which the equalization is obtained has a cylinder 71 with a piston 74 therein, the piston having the rod 75 connected thereto and there being a spring 76 inserted around the rod 5 to bear against the piston, an end plate 73 then being fitted on over the rod 5 to close the cylinder. The spring 79 is then inserted into the cylinder from the other end thereof; the adjustment device 80 is threaded into the end plate 72 and then the assembly of device and end plate is fitted to the cylinder 71 so that the adjustment plate 82 bears against the spring 79. As the rod 81 is threaded, the rotation thereof moves the plate 82 inwardly or outwardly to vary the tension of the spring 79 against the piston 74.

A line 84 is connected into the cylinder 71 near the end plate 72 and this line leads to the power cylinder 3 of the power unit 1 which is to be counter-balanced. A line 87, in turn, is connected into the cylinder 71 on the opposite side of the piston 74 from the line 84 and leads to the compressed air tanks 16. Each air tank in turn being connected as hereinabove described, by means of a line 29 to the T 30, from which the line 15 leads to the surge tank 14.

A second cylinder 91 is provided which is closed by end plates 92 and 93 and which has the spool type piston 94 therein with the piston rod 95 therefor extending through the end plate 93; the opposite end plate 92 having therein the vent or discharge 96. A line 97 from the air cylinders 16 is connected at opening 98 to the cylinder 91, and diametrically opposed thereto in the cylinder is the opening or vent 99. The line 101 branches off from the line 97 and connects into the cylinder 91 substantially centrally thereof and opposed to the line 101, on the side thereof in the direction of the openings 98 and 99, is another connection 102.

The lines 101 and 102 are so spaced and of such size that they may both open at the same time into the space surrounding the reduced diameter 103 of the spool piston 104 when the piston is located as shown in Fig. 5. There is another connection 104 into the cylinder 91 adjacent the end plate 92 and the connection 102 joins this connection and a common lead 105 connects therefrom into the clutch 116.

The clutch 116 is of any conventional type which is adapted to be expanded upon the admission of air thereto to clutch the hub of the sprocket 100. As the clutch is keyed to the shaft of the compressor 110, and as the sprocket 100 is mounted to rotate freely on this shaft when the compressor is idle, the engagement of the friction surface of the clutch with the sprocket hub causes the sprocket 100 to drive the compressor. This type of arrangement is conventional and one structure therefor is disclosed in detail in my co-pending application, Serial No. 130,982, filed of even date herewith.

The piston rod 75 has two stops 106 and 107 slidably adjustable thereon, and a lever 108 has the head 109 thereof mounted to slide along the rod 75 so as to barely contact these stops at either end of the stroke when a previously correct rela-

tionship has been manually set between pressure in power cylinder 3 and air tanks 16 for the particular well load. This lever 108 is pivoted at 111, and has a forked prong 112 to fit around a pin 113 on the piston rod 75.

In operation, should the fluid pressure in the power cylinder 3 exceed the value at which the range of the predetermined balance with the compressed air pressure has been established, such pressure pushes the piston 74 to the right to bring the stop 106 on the piston 75 into contact with the lever head 109. This, in turn, pivots the lever 108 about its pivot 111 so that the fork 112 thereof pushes the rod 95 and the spool piston 94 to the left, to place the connection 101 in communication with the space around the reduced diameter of the spool 103, and the discharge connection 102 is also placed in communication therewith so that compressed air from the cylinders 16 passes through the cylinder 103 and through the connection 105 into the clutch, not shown, to engage the sprocket 100 to drive the compressor 110.

The prime mover 22 then drives the sheave 24, and from thence, through the belt 26, the sprocket 100, and the compressor 110, builds up the air pressure in the cylinders 16, and this compressed air discharges through the line 87 to build up pressure on the right side of the piston 74 to move the piston 74 to the left.

This leftward motion of the piston 74 moves the stop 106 on the piston rod 75 so that it again barely contacts the lever head 109 at the end of the stroke. Thus the rod 75, as it returns to travel within the normal zone, slides along through the head 109 and pivots the lever 108 in a direction to move the fork 112 to the right, thereby causing the spool piston 94 to cover the connection 104 and to uncover the connection 101. This cuts off compressed air from the clutch 106 and permits the air that has been forced thereto to bleed out through the lines 105 and 104 and back through the cylinder 91 and out through the vent or discharge 96. This breaks the contact of the gripping surface of the clutch 106 with the sprocket 100, and stops the compressor 110.

Should the air pressure in the cylinders 16 increase with relation to the fluid pressure in the power cylinder 3, the piston 74 will be moved substantially to the left by the entry into the cylinder 71 of air under pressure through the connection 87. This results in the piston rod 75 moving to the left to bring the stop 107 into contact with the lever head 109 so that the fork 112 moves the piston rod 95 and spool piston 94 to the right to place the connection 98 and connection or vent 99 into communication with the space around the reduced diameter 103 of the spool so that compressed air from the cylinders 16 bleeds through the cylinder 91 to the atmosphere and reduces the pressure in the right-hand side of the cylinder 71, thereby permitting the piston 74 to move back to the normal position of Fig. 5. When this occurs it follows that the piston 74 closes the connection 102 as well as the connection 101.

As conditions vary widely in well pumping operations, the adjustment device 80, hereinabove described, is provided to adjust the length of piston travel for the varying requirements of various wells, so as to keep the stroke length within the capacity of the regulating device. Thus turning the thread rod 81 so as to move the plate 82 inwardly preloads the springs 76 and 79 for a

given load variation, and shortens the piston travel, and outward motion of the plate 82 in the control cylinder 71 lengthens the piston travel.

Broadly, this invention considers a pumping unit which is adapted to control the vertical range of the operation of the plunger of a bottom hole pump by controlling the level to which the piston in the power cylinder at the top of the well may rise; which is adapted to deliver more fluid into the power cylinder on one stroke, as on the up-stroke than on the down-stroke, by means of a self-reversing pump driven by a prime mover which rotates the impeller thereof in one direction only; and this invention further considers such a pumping unit having an automatic control or regulating device which is adapted to maintain the plane of equalization between the fluid and compressed air in the surge tank of the unit at a predetermined level.

What is claimed is:

1. A counter-balancing pumping unit comprising, a vertically extending power cylinder, a piston therein, means connected to the cylinder and adapted for connection to a bottom hole pump plunger, a plurality of vertically aligned discharge valves in said power cylinder at substantially the top thereof, a surge tank, liquid return means connected to said valves for returning liquid from above said piston to said surge tank, a self-reversing pump for transferring liquid back and forth between said power cylinder below said piston and said surge tank, an air cylinder, a compressor for supplying compressed air to said air cylinder, a line for connecting said air cylinder and surge tank, control means responsive to liquid pressure in said power cylinder below said piston to start and stop said compressor and to bleed air from said air cylinder to maintain a counter-balance between compressed air pressure and power cylinder liquid pressure below said piston, one of said valves being open while the others are closed to limit upward piston travel and said self-reversing pump having means therein to permit the pump to discharge more liquid in one direction than in the other direction.

2. A counter-balancing pumping unit comprising, a power cylinder having a piston operable therein, means connected to said power cylinder for regulating the travel of said piston therein, a surge tank, means for transferring liquid from said piston travel regulating means to said surge tank, an air cylinder connected to said surge tank, a compressor for supplying air to said air cylinder, a pump adapted while being driven in one direction to alternately transfer unequal amounts of liquid back and forth between said power cylinder and said surge tank, control means responsive to power cylinder liquid pressure and air cylinder pressure to counter-balance air and liquid pressures in said surge tank, and means for driving said pump and said compressor.

3. A counter-balancing pumping unit comprising, a power cylinder having a piston operable therein, means connected to said power cylinder for regulating the travel of said piston therein, a surge tank, means for transferring liquid from said piston travel regulating means to said surge tank, an air cylinder connected to said surge tank, a compressor for supplying air to said air cylinder, a pump adapted while being driven in one direction to alternately transfer unequal amounts of liquid back and forth between said

power cylinder and said surge tank, and control means responsive to power cylinder liquid pressure and air cylinder pressure to counter-balance air and liquid pressures in said surge tank.

4. A counter-balancing pumping unit comprising, a power cylinder having a piston operable therein, means connected to said power cylinder for regulating the travel of said piston therein, a surge tank, means for transferring liquid from said piston travel regulating means to said surge tank, an air cylinder connected to said surge tank, a compressor for supplying air to said air cylinder, and a pump adapted while being driven in one direction to alternately transfer liquid back and forth between said power cylinder and said surge tank.

5. A counter-balancing pumping unit comprising, a power cylinder having a piston operable therein, a surge tank, means for transferring liquid from said piston travel regulating means to said surge tank, an air cylinder connected to said surge tank, a compressor for supplying air to said air cylinder, a pump adapted while being driven in one direction to alternately transfer liquid back and forth between said power cylinder and said surge tank, control means responsive to power cylinder liquid pressure and air cylinder pressure to counter-balance air and liquid pressures in said surge tank, and means for driving said pump and said compressor.

6. A counter-balancing pumping unit comprising, a power cylinder having a piston operable therein, a surge tank, means for transferring liquid from said power cylinder to said surge tank, an air cylinder connected to said surge tank, a compressor for supplying air to said air cylinder, a pump adapted while being driven in one direction to alternately transfer unequal amounts of liquid back and forth between said power cylinder and said surge tank, and control means responsive to power cylinder liquid pressure and air cylinder pressure to counter-balance air and liquid pressures in said surge tank.

7. A counter-balancing pumping unit comprising, a vertically extending power cylinder, a piston therein, means connected to said power cylinder and adapted for connection to a bottom hole pump plunger, a surge tank, a self-reversing pump for transferring liquid back and forth between said power cylinder below said piston and said surge tank, an air cylinder, a compressor for supplying compressed air to said air cylinder, a line for connecting said air cylinder and said surge tank, and control means responsive to liquid pressure in said power cylinder below said piston to start and stop said compressor and to bleed air from said air cylinder to maintain a counter-balance between compressed air pressure and power cylinder liquid pressure below said piston.
